[57] **CLAIM**

The ornamental design for a window side frame extrusion, substantially as shown and described.

DESCRIPTION

FIG. 1 is an end elevation view of a window side frame extrusion embodying my new invention;

FIG. 2 is a top plan view of the extrusion shown in FIG. 1 shown fragmentarily to indicate indeterminate length; FIG. 3 is a bottom plan view of the extrusion shown in FIGS. 1-2;

FIG. 4 is a front elevation view of the extrusion shown in FIGS. 1-3; and

FIG. 5 is a rear elevation view of the extrusion shown in FIGS. 1-4.

*Fig.2.**Fig.1.**Fig.3.**Fig.4.**Fig.5.*
